RICHARD E. BOLLAM, OF PORTLAND, OREGON

ELEVATOR BOMB RACK FOR AEROPLANES

Application filed June 13, 1931. Serial No. 544,051.

My invention relates to aircraft and, more particularly, to military types, which carry more or less heavy bombs on the under side of the fuselage, which bombs are released a 5 computed distance in advance of the object to be struck. Experience with planes having machine guns mounted thereon has taught that excellent aim can be secured by arranging the rifle barrel in axial alignment with 10 that of the plane and aiming the plane itself at the object to be struck. It is impractical to arrange the bombs in fixed position beneath the fuselage, so that the latter can be released in a vertical diving flight, because 15 the bombs necessarily have to pass thru the area traversed by the propeller blades.

The object of my invention is to provide an elevating rack for bombs of this character, which rack is adapted to lower the bombs a 20 sufficient distance below the fuselage and the path of the propeller blades so that the bomb can be released in a vertical dive of the aeroplane and thus the bombs can be released directly above the object to be struck. This 25 eliminates the necessity for computing flying speed, elevation, and other disturbing factors which produce a horizontally-curved bomb flight trajectory as when bombs are released during horizontal aeroplane flight.

30 A bombing aeroplane with the bombs suspended beneath the plane has further disadvantages, one that the presence of the bomb is obvious and deception as to its character is impractical. This permits enemy gun fire 35 and hostile aeroplane to center their attack upon such bomb carrier. Further, the wind resistance of an aeroplane with the bomb suspended in this manner is substantially increased and experience has taught me that the 40 placing of a bomb on the exterior of the fuselage decreases the operating speed three to eight per cent.

The large mass arranged eccentrically with 45 respect to the longitudinal axis of mass of the plane further retards maneuverability to evade hostile attack and enemy gun fire and a further object of my invention, therefore, is to so arrange the elevating mechanism for the bomb rack so that the rack and bomb carried thereby can be wholly housed within

the fuselage at all times, except when the bomb is arranged for release. The rack and its load are further positioned with respect to the longitudinal axis of mass of the aeroplane, so that such additional mass is centered, more or less, about such axis to increase maneuverability. Inasmuch as the bomb itself represents a substantial amount of added weight which must thus be centered, 55 I arrange a plurality of stations spaced with respect to such axis of mass of the aeroplane and provide automatic means for stopping the rack when loaded at a different station than when it is empty. Thus the disposition of such mass about said axis is variable to 60 produce centralized mass during both loaded or unloaded conditions of said rack.

In order to maintain stream-line contour to the fuselage, I provide doors adapted to 70 close the opening thru which said rack ascends and descends, the exterior of such door following the stream-line contour of the plane. The door in opening preferably moves laterally outwardly in the walls of the fuselage, so as to add no interfering agency 75 to flying speed and the bomb rack is provided with a dummy door adapted to fit tightly within the opening when the rack is fully extended, so as further to maintain such flying contour of the fuselage.

A further object of my invention is to provide a device of this character which is strong, rugged and reliable in action, one which is provided with suitable and complete 80 indicators, manual and electric operating and control devices to minimize failure of action and the whole structure is designed to minimize weight to maintain high flying speed of the aeroplane.

The details of my invention are hereinafter 85 described with reference to the accompanying drawings, in which:

Fig. 1 is a longitudinal elevation of an aeroplane with portions of the fuselage shown broken away to disclose the movable 90 elevating bomb rack located therein, such figure further showing the position of the bomb in dotted lines and with respect to the propeller blades, as when such bomb is arranged 95 in extended or lowered position;

Fig. 2 is a fragmentary transverse section thru such bomb rack with the circular path described by the tip of the propeller blades and the rack in extended position, shown in dotted lines thereon;

5 Fig. 3 is a horizontal section thru a portion of the operating mechanism of such bomb rack, such view being taken approximately on the line 3—3 in Fig. 4, but broken away to show details which would otherwise be hidden or confused;

10 Fig. 4 is a foreshortened vertical section thru such bomb rack and elevating mechanism taken substantially on the line 4—4 in Fig. 3;

15 Fig. 5 is a transverse vertical section taken substantially on the line 5—5 in Fig. 3; and

Fig. 6 is a diagrammatic layout of the electrical connections of the mechanism.

20 My invention is particularly adapted to be embodied in an aeroplane of the bomber type when adapted for heavy projectiles and of correspondingly lighter type with lighter type projectiles. The type or form of such aeroplane plays little or no importance with 25 regard to my specific invention and thus the details will not be described with greater detail.

25 My invention is preferably embodied in an aeroplane *a* having a substantially continuous fuselage and, at the forward end, a propeller *b*. Extending downwardly from the under surface of the fuselage is landing gear *c*, shown as wheels as for use on land planes. 30 Housed within such fuselage is elevating mechanism for a bomb *d*, which elevating mechanism is mounted within a series of vertical members *e* arranged in pairs and at opposite sides of the plane.

35 Extending between such pairs of supporting members *e* is a horizontally-arranged spider *f*, carried by spaced lead screws *f'* mounted in bearings *f2* in horizontal members *e'* forming part of the supporting frame thereof. Such feed screws are 40 preferably arranged at the four corners of the spider and also at the middle of such spider, as is shown in Fig. 3. The operating mechanism is driven by a generator, storage battery, or some other source or accumulator of electricity, shown diagrammatically in 45 Fig. 6 as a battery *g*.

50 The mechanism is driven by an electric motor *h*, which powers the shaft *h'* extending longitudinally of such elevating mechanism. Such shaft is connected by three transverse shafts *i* to the lead screws *f'*. The connection is preferably made thru sets of worms and worm gears *i'*. Inasmuch as a single motor drives the shaft *h'* and therewith all of the transverse shafts *i*, the lead screws *f'* are operated synchronously and thus the spider is fed vertically, uniformly, and tends to be maintained in a 55 horizontal plane. When I speak of vertical

and horizontal planes, I mean to describe the position of objects when the aeroplane is flying in a horizontal plane, or is at rest.

55 The bomb *d* is carried between a pair of saddle-like receivers *j*, depending from the under side of the spider *f*. The bomb *d* is provided with a series of pockets, properly spaced with respect to such receivers, and pins *k* engage said pockets and hold the bomb in position during flight. Such pins *k* are 60 retractable and each is operated by a bell-crank lever *l*, mounted upon a pivot pin *l'*, and a pull rod *m* pivotally engages the bell crank at point *m'*. Such pull rods are moved longitudinally by forks *m2* fixed to a transverse rock shaft *m3*.

65 The releasable pins *k* are arranged in two sets, one set at the forward end of the bomb and the other towards the rear end thereof. Because the operating mechanism for each 70 set is the same, I have shown in Figs. 3, 4, and 5 the operating mechanism for only one set and it is to be understood that the structure and operation of the other set is identical with the one described. Both sets of operating mechanisms are driven from a common shaft *m4*, which extends longitudinally of the spider and said longitudinal shaft drives 75 spaced laterally-arranged shafts *m5* thru the medium of worms and worm gearing *m6*. Such shaft *m4* is driven by an electric motor *m7* carried by the spider, as is shown in Figs. 80 3 and 4.

85 Beneath the bomb-elevating mechanism the fuselage is provided with an opening closed by a door comprising a pair of sliding panels *n*, which move in guides *o*, *o'* and *o2*, being extensible laterally of the plane in such guides. Such pair of panels *n* abut substantially on the median line thru the center of the elevating rack, as is shown in Fig. 5. Such panels are moved outwardly by rack *p* and pinion *r* mechanism, as is shown in Fig. 3. Two sets of rack and pinion mechanisms are provided, one arranged at each end of the 90 bomb-elevating chamber, but in Fig. 3 the mechanism for one end only is shown, for the reason that these sets of mechanisms also are duplicates of each other. The pinions *r* are mounted upon longitudinal shafts *r'*, which extend the full length of the frame and thus 95 all four pinions are operated in synchronism. Said shafts *r* are driven by the motor *s*, (see Fig. 6).

100 In addition to the electric drive for such rack operating mechanism, and for such door-closing mechanism, I have provided a hand wheel *h2* extending within the cockpit of the aeroplane, by which the operator can 105 manually operate the bomb-elevating mechanism. Also extending into such cockpit is a hand mechanism comprising a lever *r2* capable of operating the shaft and gearing *r3*, shown at the right end of Fig. 3, for rotating 110 115 120 125 130

the shafts r' and thus the rack and pinion mechanisms p and r , respectively.

The mechanism of the devices is best explained with reference to the electrical diagram, Fig. 6, and many of the parts referred to in the electrical diagram are not shown in the disclosure of the physical apparatus and with regard to the physical construction of the remaining apparatus, because no advantage of clarity would be attained by the position and proportion of the physical elements.

As has been pointed out heretofore, the entire electrical system is shown as receiving its power from a source or accumulator of electrical energy, shown as a storage battery g . The main power line g' leads therefrom thru three branches, g_2 , g_3 and g_4 . Arranged in such branches, respectively, are distantly-actuated controls t , t' and t_2 . The control t makes and breaks the branch circuit g_2 leading to the bomb elevator motor h . The control t' makes and breaks the branch g_3 leading to the bomb releasing and securing motor m_7 and the control t_2 makes and breaks the branch g_4 leading to the door control motor s .

Each of such motors and controls are distantly operated thru auxiliary electric circuits and thus adapted for push-button control. The push button u closes the auxiliary control circuit u' , which causes the motor h to elevate, or retract the bomb rack into the fuselage. Such push button further makes the auxiliary control circuit u_2 for the closing solenoid u_3 , which forms a part of the control t_3 and closes the main service switch v in the feed circuit g' . In other words, when the push button u is depressed, it also closes an auxiliary circuit having electro-magnetic devices u_3 arranged therein, which latter are adapted to close the main control switch t and thus to energize the entire electrical system.

The push-button control u_7 functions in one particular in a manner similar to the push-button control u , inasmuch as it makes the auxiliary circuit u_2 to energize the solenoid u_3 and thus to close or make the main control switch v . It only indirectly starts the elevator mechanism downwardly. The closing of the push-button control u_7 makes the auxiliary control circuit u_8 , which energizes the left-hand solenoid of the control t_2 to move the switch elements of such latter control to the position shown in Fig. 6, and to cause the door-opening motor s to function to open the doors n . When such doors n move to their full open position, they close the switch u_{14} , which is normally open, and the closing of such switch u_9 makes the auxiliary control circuit u_{15} , which energizes the left-hand solenoid of the control t to move the switch element to the position shown in Fig. 6. The moving of such switch elements to such latter position closes the operating circuit for

the rack-opening motor h , which causes the latter to lower the bomb rack.

Arranged at the upper limit of travel of the elevator is a limit switch u_9 , which opens the rack motor circuit when the rack elevator reaches its upper limit. Similarly arranged and having a similar function is a limit switch u_{10} arranged at the lower limit of travel of such elevator mechanism.

Intermediate such limits and at a point arranged so that the bomb rack when empty will just clear the doors n , I arrange a half-way limit switch u_{11} , which functions to stop the elevator in its upward travel at a point where the empty rack will have its center of mass arranged at or near the longitudinal axis of mass of the plane as a whole. The switches u_9 and u_{10} are normally closed and the circuit is broken by contact with part of the elevator and their physical characteristics are not further described or shown and need no further explanation.

The limit switch u_{11} is shown in Figs. 3 and 4 in connection with auxiliary operating mechanism. It is essential that the elevator mechanism be not stopped when the bomb is in position and carried by such mechanism, until such mechanism has reached its upper limit of travel. To accomplish this result, I arrange a bar x , as is shown in Fig. 3, transversely of the spider and adapted for lateral reciprocation therein. A rack x' is cut from the upper face of such member and a pinion x_2 is carried by the shaft m_4 and engages such rack. The other end x_3 of the member x is flattened and is adapted to engage with the switch u_{11} arranged at one side of the spider and carried by one of the fixed structural members. With the member x positioned as shown in Fig. 3, the end x_3 will come in contact with the operating member of the switch u_{11} when the bomb support passes the horizontal plane of the door n and the rack-operating mechanism will be stopped. With the member x fully retracted, that is, moved upwardly as shown in Fig. 3, said member x will clear the switch u_{11} and will not thus actuate the latter.

As has been described heretofore, it is necessary that the motor m_7 be operated to fix the pins k in the bomb d and the shaft m_4 serves as the common physical agency for transmitting the power from the motor m_7 to the rods m for retracting the pins k . The pinion x_2 is mounted upon such shaft m_4 and the parts are arranged so that with the pins k in releasing position the latter will not hold a bomb in place and the member x will be arranged to engage the switch u_{11} . With the pins k arranged in engaging position so as to hold a bomb, the member x will be thrown by the same operating mechanism into disengaging position with respect to the switch u_{11} . The result, therefore, is that the elevator mechanism will be stopped on

its upstroke when empty at a point intermediate its upper and lower limits and will be stopped when loaded with a bomb only at its upper limit of travel.

Located physically adjacent the switch $u11$ in the bomb rack operating circuit is a switch $u12$ in the auxiliary control circuit $u13$, which latter switch is normally open. When the rack-elevating mechanism moves upwardly past the position of the switch $u11$, it closes such switch $u12$, which makes the circuit $u13$, energizes the right-hand solenoid of the control $t2$, moves the switch element of the latter to a position opposite to the position of the switch element as shown in Fig. 6, and energizes the door-operating motor s in such a manner as to cause the door n to close.

If the ascending rack mechanism does not contain a bomb it stops at such point and sufficient clearance is allowed to permit the doors to close. If the rack holds or carries a bomb, the rack continues to ascend upwardly and a sufficient time interval is permitted to elapse to permit the doors to close beneath such ascending bomb. The provision and the location of such switch $u12$ prevents the closing of the doors n when any portion of the bomb rack is below the horizontal plane of the doors, for the reason that such switch $u12$ is operated by the rack passing the point noted. A similar safety provision is provided in the operating circuit for the motor $m7$ by a switch y , which switch is located adjacent the lower limit switch $u10$, for the rack elevator mechanism. Such circuit for the motor $m7$ is held open so that the bomb cannot be released except when it is in its lowered position.

The push-button control w controls the auxiliary circuit w' , which latter circuit energizes the right-hand solenoid in the control t' and thus to arrange the switch element $v2$ of such control in the opposite position to which it is shown in Fig. 6, such push-button control w must be closed. In the electrical circuit controlling the operation of the bomb motor $m7$ in such a manner as to move the pins k toward the bomb and into engagement therewith, a limit switch $w4$ is provided for the motor $m7$, which switch $w4$ is opened when the pins are fully in engaging position, such switch also normally being closed. The pins are retracted and the bomb is released by the closing of the push-button control $w2$, which closes the auxiliary circuit $w3$ and energizes the left-hand solenoid of the control t' to move the switch element $v2$ to the position shown in Fig. 6. The operating circuit for the motor $m7$ for releasing such bomb includes the switch y heretofore described, and when such switch is closed by the lowering of the rack mechanism to its lower limit, the motor $m7$ can be energized to retract those pins by the actuation of the push button $w2$. A limit switch

$w5$ is included in such circuit, which is opened when the pins are fully retracted, thereby to break such operating circuit.

Auxiliary control circuits are provided not only to limit the voltage of the wires leading into the cockpit, but also to eliminate the necessity of the pilot's holding the switch closed during the operation of the various elements of the operating mechanism. Although the three operating mechanisms, namely the rack-operating mechanism, the door-operating mechanism and the bomb-releasing and securing mechanism are powered by separate motors, the contacts are arranged as has heretofore been explained, so that control can be secured by five buttons and one of such buttons is merely an auxiliary stop button which breaks the electrical circuit for all of the devices.

Carried on the under side of the spider f is a dummy door z , which is adapted to engage with the sides of the opening normally closed by the floor panels m and to seal said opening when the rack mechanism is extended or lowered to its limit. Said dummy door z thus seals said opening during flight with the bomb extended to maintain the streamline contour of the fuselage.

I claim:

1. In an aeroplane provided with a longitudinally-extending fuselage, a propeller alined with the said fuselage and mounted at the forward end thereof, and operating in a circular area of substantially greater diameter than that of the cross-section of the fuselage, a bomb rack, laterally stable elevator mechanism for such rack adapted to move the latter within limits and the lower or extended limit positioning the bomb beyond a prolongation rearwardly of the operating area of the propeller.

2. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, laterally stable elevator mechanism for such rack adapted to move the latter within limits, the lower or extended limit positioning the bomb outside of the fuselage and beyond a prolongation rearwardly of the operating area of the propeller.

3. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, later-

- ally stable elevator mechanism for such rack adapted to move the latter within limits, the upper or retracted limit positioning the bomb within said fuselage, the lower or extended limit positioning the bomb outside of the fuselage and beyond a prolongation rearwardly of the operating area of the propeller. 5 70
4. In an aeroplane provided with a longitudinally-extending fuselage thru which the longitudinal axis of mass of said aeroplane extends, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage and with the longitudinal axis of mass of said rack, elevating mechanism, and bomb approaching the similar axis of the aeroplane, the lower or extended limit positioning the bomb outside of the fuselage and beyond a prolongation rearwardly of the operating area of the propeller. 10 15 20 25 30 35 40 45 50 55 60 65 75 80 85 90 95 100 105 110 115 120 125 130
5. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage, and with the longitudinal axis of mass of said rack, elevating mechanism, and bomb approaching the similar axis of the aeroplane, the lower or extended limit positioning the bomb outside of the fuselage and beyond a prolongation rearwardly of the operating area of the propeller, and means for positioning the rack at one of a plurality of stations spaced laterally with respect to said longitudinal axis of mass of the aeroplane. 35 40 45 50 55 60 65 70 75 80 85 90 95 100 105 110 115 120 125 130
6. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage, and with the longitudinal axis of mass of said rack, elevating mechanism, and bomb approaching the similar axis of the aeroplane the lower or extended limit positioning the bomb outside of the fuselage and beyond a prolongation rearwardly of the operating area of the propeller, and automatic means for positioning the rack at one of a plurality of stations spaced laterally with respect to said longitudinal axis of the aeroplane. 70 75 80 85 90 95 100 105 110 115 120 125 130
7. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage, the lower or extended limit positioning the bomb outside of the fuselage and means adapted to close the opening in the fuselage. 80 85 90 95 100 105 110 115 120 125 130
8. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage, the lower or extended limit positioning the bomb outside of the fuselage and a door adapted to close the opening in the fuselage. 90 95 100 105 110 115 120 125 130
9. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage, the lower or extended limit positioning the bomb outside of the fuselage and a door consisting of two oppositely movable halves adapted to close the opening in the fuselage. 100 105 110 115 120 125 130
10. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with 120 125 130

- an opening extending thru said fuselage, elevator mechanism for such rack adapted to move the latter within limits, the upper or retracted limit positioning the bomb within said fuselage, the lower or extended limit positioning the bomb outside of the fuselage, means adapted to close the opening in the fuselage and means synchronized with said elevator mechanism for operating said means with relation to the operation of said elevator mechanism.
11. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage, the lower or extended limit positioning the bomb outside of the fuselage, a door adapted to close the opening in the fuselage and means synchronized with said elevator mechanism for operating said door with relation to the operation of said elevator mechanism.
12. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage, the lower or extended limit positioning the bomb outside of the fuselage, means adapted to close the opening in the fuselage and a sealing member adapted to seal said opening when the rack is extended to its lower limit.
13. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage, the lower or extended limit positioning the bomb outside of the fuselage, means adapted to close the opening in the fuselage and a sealing member operated by the elevator mechanism adapted to seal said opening when the rack is extended to its lower limit.
14. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage, the lower or extended limit positioning the bomb outside of the fuselage, said rack and elevator mechanism comprising a plurality of lead screws extending transversely of the fuselage, a spider element carried thereby, a bomb support depending from said spider element, releasable bomb-securing means associated with the latter, said securing means comprising a pin movably secured to said support.
15. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage, the lower extended limit positioning the bomb outside of the fuselage, said rack and elevator mechanism comprising a plurality of lead screws extending transversely of the fuselage, a spider element carried thereby, a bomb support depending from said spider element, releasable bomb-securing means associated with the latter, said securing means comprising a pin movably secured to said support and distant operating means for moving said pin into and out of bomb-engaging position.
16. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage, the lower or extended limit positioning the bomb outside of the fuselage, said rack and elevator mechanism comprising a plurality of lead screws extending transversely of the fuselage, a spider element car-

ried thereby, a bomb support depending from said spider element, releasable bomb-securing means associated with the latter, said securing means comprising a plurality of retractable pins movably secured to said support.

17. In an aeroplane provided with a longitudinally-extending fuselage, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage, the lower or extended limit positioning the bomb outside of the fuselage, said rack and elevator mechanism comprising a plurality of lead screws extending transversely of the fuselage, a spider element carried thereby, a bomb support depending from said spider element, releasable bomb-securing means associated with the latter, said securing means comprising a plurality of retractable pins movably secured to said support and distant operating means for moving said pins simultaneously into and out of bomb-engaging position.

18. In an aeroplane provided with a longitudinally-extending fuselage thru which the longitudinal axis of mass of said aeroplane extends, a propeller alined with the said fuselage and mounted at the forward end thereof, and operating in a circular area of substantially greater diameter than that of the cross-section of the fuselage, a bomb rack mounted within such fuselage, above and in vertical alinement with an opening extending thru said fuselage, elevator mechanism for such rack adapted to move the latter within limits, the upper or retracted limit positioning the bomb within said fuselage and with the longitudinal axis of mass of said rack, elevating mechanism, and bomb approaching the similar axis of the aeroplane, the lower or extended limit positioning the bomb outside of the fuselage and beyond a prolongation rearwardly of the operating area of the propeller, said rack and elevator mechanism comprising a plurality of lead screws extending transversely of the fuselage, a spider element carried thereby, a saddle-like bomb support depending from said spider element, releasable bomb-securing means associated with the latter, said securing means comprising a plurality of retractable pins movably secured to said support, distant operating means for moving said pins simultaneously into and out of bomb-engaging position, a door consisting of two oppositely movable halves adapted to

close the opening in the fuselage, means synchronized with said elevator mechanism for operating said door with relation to the operation of said elevator mechanism, a sealing member operated by the elevator mechanism and carried by said spider adapted to seal said opening when the rack is extended to its lower limit.

19. In an aeroplane provided with a longitudinally-extending fuselage, a bomb rack, laterally stable elevator mechanism for such rack adapted to move the latter within limits and the upper or retracted limit positioning the bomb within said fuselage.

20. In an aeroplane provided with a longitudinally-extending fuselage thru which the longitudinal axis of mass of said aeroplane extends, a bomb rack mounted within such fuselage, above and in vertical alinement with an opening extending thru said fuselage, laterally stable elevator mechanism for such rack adapted to move the latter within limits, the upper or retracted limit positioning the bomb within said fuselage and with the longitudinal axis of mass of said rack, elevating mechanism, and bomb approaching the similar axis of the aeroplane and the lower or extended limit positioning the bomb outside of the fuselage.

In testimony whereof he has affixed his signature.

RICHARD E. BOLLAM.
